(57) **CLAIM**

The ornamental design for a vial-like liquid container having dual liquid applicators with removable caps, as shown and described.

DESCRIPTION

FIG. 1 is a top, front and side perspective view of a vial-like liquid container having dual liquid applicators with removable caps embodying the present invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof;

FIG. 8 is an exploded, top, front, and side perspective view of a vial-like container having dual liquid applicators with removable caps at opposite ends thereof, with the end caps removed and displaced from the opposite ends of the vial-like container;

FIG. 9 is a right side elevational view thereof;

FIG. 10 is a left side elevational view thereof;

FIG. 11 is a front side elevational view thereof;

FIG. 12 is a rear elevational view thereof;

FIG. 13 is a top plan view; and,

FIG. 14 is a bottom plan view thereof.

The even length broken lines in the drawings illustrate a portion of the container pump assembly of the vial-like liquid container having dual liquid applicators with removable caps and form no part of the claimed design. The long-dash, short-dash broken lines shown in the drawings illustrate an exploded configuration of the vial-like liquid container having dual liquid applicators with removable caps and forms no part of the claimed design.
